M. E. BAILEY

TCOL FOR REPLACING TRANSMISSION COVERS ON FORD CARS

Filed March 16, 1922

INVENTOR

INVENTOR
Dr. E. Bailey
Merith E. Bailey

UNITED STATES PATENT OFFICE.

MERITT E. BAILEY, OF BURBANK, CALIFORNIA.

TOOL FOR REPLACING TRANSMISSION COVERS ON FORD CARS.

Application filed March 16, 1922. Serial No. 544,092.

To all whom it may concern:

Be it known that I, MERITT E. BAILEY, a citizen of the United States, residing at Burbank, in the county of Los Angeles 5 and State of California, have invented certain new and useful Improvements in a Tool for Replacing Transmission Covers on Ford Cars, of which the following is a specification.

10 This invention relates to tools especially adapted for use when replacing the transmission cover of a Ford transmission.

An important object is to provide a tool having novel means to hold the transmission 15 bands, springs and associated elements in position while the cover is being replaced.

A further object is to provide a tool of 20 the class described which may be readily and conveniently applied and disconnected and, which when in position, will effectively hold the several parts in position so that the time required to replace the transmission cover will be reduced to a minimum.

25 A further object is to provide a tool of the class described which is of highly simplified construction, simple to operate and cheap to manufacture.

Other objects and advantages of the invention will be apparent during the course 30 of the following description.

In the accompanying drawing forming a part of this application and in which like numerals are employed to designate like parts throughout the same,

35 Figure 1 is a perspective of the improved tool applied.

Figure 2 is a vertical sectional view through the tool applied.

Figure 3 is a perspective of the tool.

40 In the drawing wherein for the purpose of illustration is shown a preferred embodiment of the invention, the numeral 5 designates a transmission cover within which the usual drums 6 are arranged. The 45 bands 7 are arranged about the drums and are provided with upwardly directed ears 8 having slots 9 through which the operating shafts 10 are extended, the said shafts having their terminal portions threaded for

50 engagement with nuts 11 which form a means whereby the bands may be adjusted as the occasion requires. Washers 12 are arranged between the nuts 11 and the ears 8 and are provided with notches which en-

gage the nuts 11 so that the nuts are securely held in position. 55

The invention forming the subject matter of this application is in the nature of a tool formed from a single piece of flat metal 14 having a plurality of downwardly directed lugs 16 which engage the inner sides of the ears 8 at opposite sides of the shafts 10 whereby to hold the bands in position about the drums during the replacement of the cover 5. The improved tool is also 60 provided along its longitudinal edges with laterally projecting gradually tapered arms 18 which are received within the slots 9 in the ears 8 whereby to hold the bands in properly spaced relation with relation to 65 each other. The arms 18 at the right of the tool also engage the washers 12 so as to hold the same in position and the arms 18 at the right are somewhat shorter than 70 those at the left of the tool for convenience 75 in applying the tool.

In order that the tool might be securely held in position, I have provided the same with longitudinal and transverse incisions 19 and 20 respectively which provide a pair 80 of arms 21 extended downwardly and curved longitudinally for engagement with the intermediate spring of the series of three springs between the bands. The downwardly extending attaching arms 21 have 85 their terminal portions curved outwardly so as to permit the arms to be slipped over the intermediate spring 23 with convenience.

In operation, the tool is applied to the intermediate spring and the laterally projecting arms 18 are engaged with the ends of bands and with the washers so as to hold the bands and other parts in position. Of course the downwardly extending lugs 16 formed along the longitudinal edges of 95 the sheet metal plate engage the ends of the springs and thereby hold the same in position so that the cover may be applied. 90

It will be seen that by the use of the improved tool the time required to replace 100 the transmission cover is reduced to a minimum.

I claim:—

1. A transmission tool consisting of an elongated piece of metal having its longitudinal edges formed with downwardly extending spaced lugs adapted for engaging 105 the springs of the bands of a planetary

transmission whereby to hold the springs in position, said elongated piece of metal being provided between said spaced lugs with laterally projecting arms adapted for engaging the ears of the transmission bands.

2. A transmission tool consisting of an elongated piece of metal having its longitudinal edges formed with downwardly extending spaced lugs adapted for engaging the springs of the bands of a planetary transmission whereby to hold the springs in position, said elongated piece of metal being provided between said spaced lugs

with laterally projecting arms adapted for engaging the ears of the transmission bands, 15 said piece of metal being provided between its longitudinal edges with downwardly extending spring arms adapted for engaging one of the springs of the transmission bands.

In testimony whereof, I have affixed my 20 signature in the presence of two witnesses.

MERITT E. BAILEY.
